UNITED STATES PATENT OFFICE

2,440,389

WATER SAVER

Walter Mark Anderson, Sr., Montgomery, Ala.

Application August 14, 1944, Serial No. 549,359

4 Claims. (Cl. 4—57)

1

The device forming the subject matter of this application serves to provide novel structural means for closing the buoyant valve of a closet flush tank, or other flush tank, prematurely, to effect a saving of water, a consideration desirable in view of present war conditions. A further object of the invention is to supply novel means whereby the closing of the aforesaid valve may be brought about either at the will of an operator, or through the instrumentality of an auxiliary float which, as the level of the water in the tank falls, becomes a weight, imposed upon the valve.

It is within the province of the disclosure to improve generally and to enhance the utility of devices of that type to which the present invention appertains.

With the above and other objects in view, which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

The drawings show a preferred but not mandatory form, and therein the invention is illustrated in a single figure, which is an elevation, parts being broken away.

The numeral 1 has been used to designate a flush tank, provided with a flushing-water outlet 2, the outlet having a valve seat 3, which includes a lateral extension 4, whereunto is connected a vertical pipe 5, adapted to receive water from a ball-cock (not shown), after a buoyant valve 6 has settled upon the seat and closed it against the outflow of the accumulated water 7. The refilling pipe for the closet trap (not shown) appears at 15.

The mechanism for raising the valve 6, to the end that it may float on the water and permit the water to be discharged by way of the outlet 2, comprises a stem 8, threaded into the valve 6 and slideable in a guide bracket 18 secured to the pipe 5, the stem having a head 9 at its upper end, disposed above a lateral eye 10 on a link 11, the eye being slideable along the stem. The upper end of the link 11 has a head 12, cooperating with any suitable mechanism 14, functioning to raise the link and permit the valve 6 to float, at the will of an operator.

Up to this point, the description relates to an old and well known structure, the resulting operation being of common knowledge. When the valve 6 is raised by an operator, it floats until

2

a predetermined quantity of water has escaped through the outlet 2: and then the valve closes on the seat 3, due to the weight of the member 6 and to suction through the outlet.

Assuming that conditions demand economy in the use of water, if the valve 6 can be caused to close earlier than would be required for the discharge of the aforesaid predetermined quantity, water will be saved. An earlier closing of the valve 6 may be obtained if an increased downward pressure is imposed upon it.

In the present invention, increased downward pressure is put on the valve 6 by adding weight to it, or by thrusting it downwardly, at the will of an operator.

A laterally extended bracket 17 is secured to the upper portion of the pipe 5, an elongated guide tube 50 being fixed in the bracket. In the guide 50 and in the top of the flush tank 1, an operating member 19, preferably in the form of a rod, is mounted for reciprocation. The rod 19 has a push button 20 at its upper end. At its lower end, the rod 19 is supplied with a transverse finger 21, terminating in a loop 22, receiving the stem 8 slidably.

At any time during the discharge of the water in the tank 1, through the outlet 2, the operator may depress the rod 19, thereby putting pressure on the valve 6, and causing it to engage the seat 3. The valve 6 thus may be closed before the full quantity of water in the tank 1 has been discharged, and water will be saved. If the operator finds that more water is required to bring about a proper flushing, he can open the valve 6 by way of the stem 8, the link 11 and the mechanism 14, and then close the valve 6 again, before the full quantity of water has run out, the rod 19 being given another downward thrust.

In order to economize water, it is not necessary that the rod 19 be actuated by an operator. An abutment 23 is carried by the rod 19, for slideable adjustment, but the abutment normally has a fixed height considered relatively to the valve 6, since a spacer 24 is disposed about the rod 19, between the abutment and the finger 21 of the rod, the spacer being preferably a spiral wire.

A float 25 is provided, and is carried by a radius arm 26, operatively connected to the ball-cock 50 (not shown) in the customary way.

A saddle 27 is secured to the radius arm 26, a depending thrust rod 28 having its upper end pivotally connected at 29 with the saddle. The thrust rod 28 has a transverse arm 30 at its lower end, the arm terminating in an eye 31, which is

slidably mounted on the operating member 19, above the abutment 23.

Assuming that the level of the water falls, until the float 25 no longer is buoyantly supported, the float, the parts 27 and 28 which it carries, constitute a weight which, being superposed on the abutment 23, causes the valve 6 to close earlier than would be the case otherwise, a quantity of water less than the aforesaid predetermined quantity being permitted to escape through the outlet 2.

The amount of water that escapes before the float 25 and associated parts become a weight, may be varied by changing the length of the spacer 24, thereby to raise or lower the abutment 23. A piece may simply be clipped off the spacer 24, or one spacer may be substituted for another, the spacers being of different lengths.

It will be understood that the specific flush tank and operating details for the stem 8 may be varied as occasion or the existing installations may require, without departing from the spirit of the invention.

Having thus described the invention, what is claimed is:

1. In a water saving device, a flush tank having an outlet, a buoyant valve controlling the outlet, a valve operating member disposed above the valve and supported thereby, said member being movable relatively to the valve, a portion of said member being exposed for depression by an operator, to secure a premature closing of the valve, an abutment on said member, a float and mechanism for mounting the float in the tank for movement responsive to the rise and fall of the liquid therein, weight means comprising a part slidably mounted on said member and engageable with the abutment, when the level of the water in the tank falls, thereby to superpose

an added weight on the valve and to secure a premature closing of the valve.

2. In a water saving device, a flush tank having an outlet, a buoyant valve controlling the outlet, an operating member mounted for vertical movement, the operating member being disposed above the valve and being supported thereby, an abutment movable along the operating member, and including spacing means, a weight slidably 5 along the operating member and engageable with the abutment upon depletion of water in the tank, to promote a premature closing of the valve, and a float connected to the weight and responsive to changes of level in the tank.
- 10 3. A water saving device constructed as set forth in claim 2, and wherein said means is a spacer removably mounted on the operating member and supported thereby, the upper end of the spacer engaging the abutment.
- 15 4. A water saving device, constructed as set forth in claim 2, and wherein said means is a severable coiled wire disposed about the operating member and supported thereby, the upper end of the wire engaging the abutment.

25 WALTER MARK ANDERSON, SR.
